UNITED STATES PATENT OFFICE.

WILLY HORNAUER, OF NEUKOLLN, GERMANY, ASSIGNOR TO TELEGRAPHIE-SELLSCHAFT MIT BESCHRÄNKTER HAFTUNG SYSTEM STILLE, OF BERLIN, GERMANY.

MAGNET CARRIER FOR ELECTROMAGNETIC TALKING MACHINES.

Application filed June 20, 1925, Serial No. 38,558, and in Germany July 3, 1924.

This invention relates to an electro-magnetic talking machine of the kind in which the record is impressed magnetically on a steel wire which passes through a magnet box as it is wound from one spool to another.

The object of the invention is to produce a carrier for the magnet box which enables the latter to participate in the changes which 10 the position of the wire undergoes as it traverses the spools and as one spool grows while the other is diminished.

This object is achieved according to the invention by the provision of a traverse 15 mechanism on which the magnet box is swivelly held in a pivoted arm so that it can follow the traversing movements of the wire and at the same time turn about its point of support and shift laterally together with 20 the latter.

Fig. 1 of the accompanying drawings is a diagram showing the spools and two different positions of the magnet box,

Fig. 2, a plan of the magnet box and the 25 carrier arms, and

Fig. 3, a side view of the mechanism, partly in section.

The record wire D moves from one to the other of two spools A and B and changes 30 its position gradually, as indicated in Fig. 1, as one spool grows and the other is diminished. At the same time the wire traverses the spools to and fro in the axial direction of the same.

To enable the magnet box C to change its 35 position accordingly, it is mounted by means of trunnions E in a fork F. The latter has a pivot pin G whereby it is swivelly held in a socket H at the free end of an arm J.

This arm has at the opposite end a socket L 40 whereby it is pivotally held on a pin M ris-

ing from a carrier N which reciprocates, as indicated by the arrows S, on a vertical spindle O under the influence of a heart-shaped cam P, the carrier N being supported 45 on the cam by means of a roller R. The carrier N and the cam P constitute a traverse mechanism which causes the magnet box to follow the wire from one side of the spool to the other. Meanwhile, as the diameters of the spools vary, the arm J turns, say 50 from the position IV in Fig. 2 to the position V, and the magnet box, while being thus bodily translated round the pivot M, also changes its angular position about the 55 pivot G, as indicated in Fig. 2 by the lines I, II and III.

I claim:

1. In an electro-magnetic talking-machine of the character described, the combination 60 with a magnet box and a record wire passing through said magnet box from one spool to another, of a traverse mechanism, and means for supporting the magnet box on said traverse mechanism so that it can turn 65 about its supporting point and shift together with the latter in a plane at right angles to the traversing movement, substantially as and for the purpose set forth.

2. In an electro-magnetic talking-machine 70 of the character described, the combination with a magnet box and a record wire passing through said magnet box from one spool to another, of a vertically adjustable carrier, a heart-shaped cam supporting said 75 carrier so as to reciprocate the same on being rotated, an arm pivoted to said carrier, and a fork swivelled to the free end of said arm and holding said magnet box so that the latter can follow the changes in the position 80 of the wire.

WILLY HORNAUER.
